UNITED STATES PATENT OFFICE.

OTTO A. HOKANSON, OF WOODSTOCK, ILLINOIS, ASSIGNOR TO WOODSTOCK TYPEWRITER COMPANY, OF WOODSTOCK, ILLINOIS, A CORPORATION OF ILLINOIS.

RIBBON VIBRATOR FOR TYPEWRITERS.

Application filed September 1, 1921. Serial No. 497,647.

To all whom it may concern:

Be it known that I, OTTO A. HOKANSON, a citizen of the United States, residing at Woodstock, in the county of McHenry and 5 State of Illinois, have invented certain new and useful Improvements in Ribbon Vibrators for Typewriters, of which the following is a specification.

This invention relates to mechanism for 10 controlling the inking ribbon for typewriters and especially that portion of the mechanism by which the ribbon is moved to cover and uncover the printing point. The invention is particularly applicable to typewriters 15 which may be folded for compacting. It has for its object the provision of mechanism of the class named which shall be of improved construction and operation. It is exemplified in the combination and arrangement of parts shown in the accompanying drawings and described in the following specification, and is more particularly pointed out in the appended claims.

In the drawings—

25 Fig. 1 is a vertical sectional view of a portion of a typewriter embodying one form of the present invention;

Fig. 1^a shows a detail of construction;

30 Fig. 2 is a vertical sectional view of a portion of the typewriter illustrated in Fig. 1 showing the ribbon vibrator mechanism in front elevation; and

35 Fig. 3 is a vertical sectional view of the typewriter shown in Figs. 1 and 2, with the platen carriage arranged in folded position.

As illustrated, the numeral 10 designates the main or base frame of a typewriter having a pair of arms 11 pivoted thereon at 12 for supporting the platen carriage frame 13 so that it may be swung about the pivots 12 into and out of operating position. The frame 13 is provided with ways 14 on which the platen carriage 15 slides transversely of the machine carrying therewith the platen 16. Key levers 17 are pivoted at 18 on the main frame 10 and are connected by sub-levers 19 and links 20 with type bars 21 which are mounted on a type bar segment 22 supported by the main frame.

50 Ribbon spools 23 are journaled at 24 on brackets 25 formed on the side walls of the main frame and a ribbon 26 is guided between the spools 23 by arms 27 which carry the ribbon adjacent the platen at its central portion near the printing point. The rib-

bon 26 is supported by loops 28 formed on a ribbon vibrator 29 which is mounted to slide vertically upon a vibrator frame or supporting plate 30. The downward movement of the vibrator 29 is limited by lugs 31 on the plate 30 and the vibrator is guided in its sliding movement by tongues 32 which are bent about the edges of the plate.

The arms 27 and the plate 30 are carried by a rod 33 which extends transversely of the main frame and has its ends journaled in the side walls thereof. The rod 33 may turn in its bearings to permit the arms 27 and the ribbon vibrator support 30 to swing from their operating position shown in Fig. 1 to the folded position shown in Fig. 2. The parts are held in operating position by a catch 34 which releasably engages the vibrator supporting plate.

A rocking bar 35 is pivoted in the side walls of the typewriter frame and extends transversely thereof adjacent the rear wall. The bar 35 carries a pair of arms 36 which have a pin and slot connection 37 with arms 38 pivoted at 39 on the side walls of the frame. Links 40 are connected with the arms 38 and support a universal bar 41 disposed beneath the key levers 17. Operation of the key levers oscillates the bar 35 which is returned to its normal position after each key lever operation by springs 42. An arm 43 projects upwardly from the bar 35 and is connected by a pin and slot connection 44 with a link 45. The link 45 is pivoted at 46 to a downwardly projecting ear 47 formed upon an arm 48 which is pivotally mounted at 49 on an upwardly projecting arm 50 pivotally carried on the bar 33. The arm 43 is provided with a laterally bent lug 51 which limits the rearward movement of the link 45 upon its pivot 44 while permitting forward movement of the link about its pivot independently of the arm 43.

A segment 52 is mounted on the pivot 49 adjacent the arm 48 and the arm 48 carries a pin 53 arranged to engage depressions 54 in the segment 52 and hold the segment and arm for movement in unison with one another. The arm 48 is spring-pressed against the segment 52 but yields laterally to permit movement of the pin 53 from one depression 54 to another. A spring 55 is connected to the segment 52 tending to draw the segment in a counterclockwise direction, as viewed in Fig. 1, and the movement of

the segment under the influence of the spring 55 is limited by a lug 56 which projects into a slot in the rear wall of the frame 10. The pin 53 is resiliently pressed into 5 the openings 54 by a spring 57 and a finger-piece 58 projects from the end of the arm 48 by means of which the arm may be shifted relative to the segment 52 to bring the pin 50 into engagement with the different 10 depressions 54.

When the pin 53 is in the lowermost depression 54 the link 45 will be in its rear-most position in contact with the lug 51. When the parts are thus arranged the operation 15 of a key lever will move the arm 43 forwardly carrying the link 45 therewith and rotate the arm 48 and segment 52 in a clockwise direction. The segment 52 is provided with a laterally extending arm 59 20 which is pivotally and detachably connected with a pin 60 on the vibrator 29. The movement of the segment will lift the vibrator 29 to bring the ribbon 26 over the printing point at the time that the type bar strikes 25 the platen. When the parts are adjusted as shown in Fig. 1 of the drawings, the lower portion of the ribbon will be brought into printing position by the vibrator. If the arm 48 is shifted to bring the pin 53 30 into the middle depression 54 the link 45 will be swung forwardly a short distance away from the lug 51 so that when a key lever is depressed the upward movement of the ribbon vibrator will take place at a 35 later time in the cycle of operation of the parts and the upward movement will be of less extent than when the pin is in engagement with the lowest depression 54. This will bring the upper portion of the ribbon 40 into printing position, and where a two color ribbon is employed the intermediate depression 54 is usually employed for writing on the black zone of the ribbon, while the lower depression is used for writing on 45 red. When the arm 48 is shifted to the uppermost depression 54 the operation of a key lever will not affect the ribbon vibrator, which will therefore remain stationary when a key is struck. This adjustment is commonly 50 employed for cutting stencils.

As shown in Fig. 1, the arm 59 is provided with a bifurcated head 61 which fits over the pin 60 to operate the vibrator when the parts are in their operating position. 55 When the catch 34 is disengaged to permit the vibrator and its support to swing by gravity into folded position, as shown in Fig. 3, the pin 60 moves out of engagement with the bifurcated head 61 permitting folding 60 of the ribbon guides and vibrator prior to the folding of the platen carriage frame. This removes the guides and vibrator out of the path of the carriage frame so that they will not interfere with the folding 65 operation of the frame parts.

A link 62 is pivotally connected at 63 to the arm 50 and the forward end of the link 62 is pivoted to the lower end of an arm 64 which is supported at 65 on an extension 66 of the bracket 25. A spring 67 70 normally draws the arm 64 forwardly but the arm is held against movement when the parts are in operating position by a pin 68 which engages a shoulder 69 at the upper end of the arm 64. The pin 68 is carried by the pivoted arm 11 of the platen carriage frame and is arranged so that as soon as the platen carriage frame is raised from the full to the broken line position shown in Fig. 1, the arm 64 will swing to the broken line position in that figure, drawing the link 62 forwardly and swinging the arm 50 in a counterclockwise direction about the rod 33. This will shift the segment 52 with its bifurcated connecting head 61 from the position shown in Fig. 1 to that shown in Fig. 3, bringing the bifurcated head 61 into re-engagement with the pin 60 before the platen carriage frame has moved out of the path of the type bars. The bifurcated head 61 will thus be held resiliently in contact with the pin 60 and hold the vibrator and ribbon guides in folded position. When the arm 50 and the segment 52 are 95 swung forwardly the upper end of the link 45 will be drawn upwardly and forwardly into the position shown in Fig. 3, the link sliding upon the arm 43 by means of its pin and slot connection therewith.

The link 45 preferably carries a cam projection 70 which remains in contact with the lug 51 for all positions of the link. When the platen carriage frame is folded to bring the platen over the keyboard in its compacted position a lug 71 formed on the arm 11 will be brought into the opening of a hook 72 projecting forwardly from the arm 64 to lock the arm 64 in its forward position, as shown in Fig. 3. This will provide a positive lock for the folded ribbon supports which will supplement the action of the spring 67 and prevent any movement of the ribbon supports while the frame parts are in their folded position. When the platen carriage frame is returned to its operating position the ribbon supports will be released from the locking lug 71 and may be manually swung rearwardly and upwardly to their operating position in which they will be held by the catch 34. The arrangement provides a folding typewriter in which the ribbon mechanism is all carried on the main or base frame and in which the folding of the frame parts does not break the operative connections of the ribbon mechanism. Means is also provided for positively locking the ribbon supports in a folded position during the time that the typewriter is folded so that there is no danger of these supports becoming bent or 130

- otherwise injured while accidentally moved so as to project above the other portions of the typewriter. After the lock is released the parts are still resiliently held in folded position, thus avoiding danger of their being raised into the path of the platen carriage frame during its movement to operating position. The guides are held folded by the spring 67 until the platen carriage frame is in place and the guides are raised by the operator into engagement with the retaining catch 34.
- I claim:—
1. In a compactible typewriter, a main frame having a platen carriage frame movably mounted thereon, a ribbon vibrator support foldably mounted on said main frame for movement into a compacted position, a ribbon vibrator on said support, key levers on said main frame, and an operative means connecting said key levers with said vibrator, said vibrator when folded being automatically movable by the folding movement of said vibrator support out of engagement with said operative connection.
  2. In combination, a typewriter having a ribbon vibrator foldably mounted thereon for movement into a compacted position, and actuating mechanism for said vibrator, said vibrator when folded being automatically movable by the folding movement thereof out of operative engagement with said actuating mechanism.
  3. The combination with a typewriter having two frame parts foldable relative to one another, of a ribbon vibrator foldably mounted on one of said frame parts for movement into compacted position independently of the other frame part, and an actuating member for said vibrator carried on the same frame part therewith, said vibrator when folded being automatically movable by the folding movement thereof out of operative engagement with said actuating member.
  4. The combination with a typewriter having a main frame and a platen carriage frame movably mounted thereon, of a ribbon vibrator foldably mounted on said main frame for movement into compacted position, and actuating mechanism for said vibrator on said main frame, said vibrator when folded being automatically movable by the folding movement thereof out of operative connection with its actuating mechanism.
  5. The combination with a typewriter having a main frame and a platen carriage frame foldably mounted thereon, of a ribbon vibrator foldably mounted on said main frame, and actuating mechanism for said vibrator carried by said main frame, said vibrator being movable out of operative engagement with its actuating mechanism during a portion of the folding movement of
  6. The combination with a typewriter having two frame parts compactible relative to one another, of a ribbon vibrator for said typewriter, actuating mechanism for said vibrator, said vibrator and its actuating mechanism being separated during a compacting movement of said typewriter parts and means for reconnecting said parts after separation and during said compacting operation.
  7. The combination with a typewriter, of a ribbon vibrator foldably mounted thereon, actuating mechanism for said vibrator, said vibrator and its actuating mechanism, being separable during a folding operation of said vibrator and means for subsequently reconnecting said vibrator and its actuating mechanism during the folding operation of said typewriter.
  8. The combination with a typewriter, of foldable ribbon mechanism thereon, and actuating means for said ribbon mechanism, said ribbon mechanism and its actuating means being operatively disconnected from one another and subsequently brought into re-engagement during the folding operation of said typewriter.
  9. The combination with a folding typewriter having folding means thereon for manipulating a ribbon, of actuating means for said ribbon manipulating means, said actuating means comprising a device for holding said ribbon manipulating means in its folded position when said typewriter is folded.
  10. The combination in a foldable typewriter, of foldable means thereon for manipulating a ribbon, and means for locking said ribbon manipulating means in its folded position, said locking means being automatically operable by the folding of said typewriter.
  11. The combination with a typewriter having two frame parts foldable relative to one another, of foldable ribbon manipulating means mounted on one of said frame parts, and means for resiliently holding said ribbon manipulating means in folded position during folding operation of said frame parts relative to one another.
  12. The combination with a typewriter having frame parts foldable relative to one another, of ribbon manipulating means foldably mounted on one of said frame parts, means for holding said ribbon manipulating means in folded position during the folding of said frame parts relative to one another, and means for locking said ribbon manipulating means in folded position when said frame parts are folded.
  13. The combination with a typewriter

- 2 having frame parts movable relative to one another into compacted position, of ribbon manipulating means carried by one of said frame parts and movable thereon into compacted position, and actuating means for said ribbon manipulating means, said actuating means being arranged to retain said ribbon manipulating means in its folded position during folding of said frame parts.
- 10 14. In a typewriter having frame parts foldable relative to one another, a ribbon support mounted on one of said frame parts and foldable thereon, means actuated during the first part of the folding movement of said frame parts relative to one another for holding said ribbon support in folded position during the folding movement of said frame parts, and means for automatically locking said ribbon support in folded position when said frame parts are folded.
- 15 15. In a typewriter, a main frame having a platen carriage frame foldably mounted thereon, a ribbon support foldably mounted on said main frame, and means controlled by said platen carriage frame for retaining said ribbon support in folded position for a period of time during the folding of said platen carriage frame.
- 20 16. In a typewriter, a main frame having a platen carriage frame foldably mounted thereon, a ribbon support foldably mounted on said main frame, means controlled by said platen carriage frame for retaining said ribbon support in folded position for a period of time during folding of said platen carriage frame, and means controlled by said platen carriage frame for locking said ribbon support in folded position when said platen carriage frame is folded.
- 25 17. The combination with a typewriter having a main frame and a platen carriage frame foldably mounted thereon, of a ribbon vibrator support foldably mounted on said main frame, a vibrator on said support, actuating means for said vibrator, and means for causing said actuating means to retain said vibrator in folded position for a period of time during the folding of said platen carriage frame.
- 30 18. In combination, a typewriter having a main frame and a platen carriage frame foldably mounted thereon, of a ribbon vibrator foldably mounted on said main frame, actuating means for said vibrator disconnectable therefrom when said vibrator is moved to folded position, and means for re-connecting said actuating means with said vibrator to retain said vibrator in folded position when said platen carriage frame is folded.
- 35 19. In combination, a typewriter having a main frame and a platen carriage frame foldably mounted thereon, a ribbon vibrator foldably mounted on said main frame, actuating means for said vibrator carried by
- 40 said main frame, said vibrator being movable out of operative engagement with its actuating means when said vibrator is folded, means for re-connecting said actuating means with said vibrator to retain said vibrator in folded position during the folding movement of said platen carriage frame, and means for locking said vibrator in folded position when said platen carriage frame is folded.
- 45 20. In a typewriter, a main frame having a platen carriage frame foldably mounted thereon, a ribbon support foldably mounted on said main frame, ribbon manipulating means movably carried by said support, actuating means for said ribbon manipulating means, said ribbon manipulating means being disconnected from its actuating means when the support for said manipulating means is folded, and means controlled by said platen carriage frame for re-connecting said ribbon manipulating means and its actuating means when said platen carriage frame is folded.
- 50 21. In combination, a typewriter having a main frame and a platen carriage frame foldably mounted thereon, of a ribbon vibrator support pivoted on said main frame and movable into compacted position thereon, a ribbon vibrator slidably mounted on said support, key-operated actuating means for said vibrator carried by said main frame, said vibrator being disconnected from its actuating means when folded, resilient means for restoring the connection between said vibrator and its actuating means during the first part of the folding movement of said platen carriage frame, and means for locking said vibrator and its actuating mechanism in engagement with one another while said platen carriage frame is folded on said main frame.
- 55 22. Ribbon vibrator mechanism for a typewriter comprising a ribbon carrier, a support for said carrier, an arm for oscillating said carrier on its support, and a pivotal support for said arm, said pivotal support being movable to accommodate said actuating arm to different positions of said ribbon carrier support.
- 60 23. In combination, a typewriter having a ribbon vibrator support movably mounted thereon, a ribbon vibrator movably mounted on said support, an oscillatory member for actuating said vibrator, and a shiftable support for said oscillatory member to accommodate said oscillatory member to different positions of said vibrator.
- 65 24. A typewriter having a ribbon vibrator foldably mounted thereon, an oscillatory member for actuating said vibrator, said vibrator being movable out of engagement with said oscillatory member when said vibrator is folded, and a movable support for said oscillatory member to permit re-en-

- gagement of said oscillatory member with said vibrator while said vibrator is in folded position.
25. In a typewriter, a platen carriage support, a ribbon vibrator, an oscillatory member for actuating said vibrator, an arm adjustably connected with said oscillatory member for actuating said member various amounts, key levers for said typewriter, an operative connection between said key levers and said arm, and a support for said oscillatory member and its actuating arm, said support being shiftable relative to said platen carriage support.
- 15 26. In a typewriter, a platen carriage support, a ribbon vibrator movable to different positions on said typewriter, a pivotally mounted segmental member for operating said vibrator, an arm pivoted concentrically with said operating member and adjustably connected therewith for moving said operating member various amounts, key levers, an operative connection between said arm and said key levers, and a support for said operating member and arm, said support being shiftable relative to said platen carriage support to accommodate said support to different positions of said vibrator.
25. In a typewriter, a platen carriage support, a ribbon vibrator foldably mounted thereon, an oscillatory member for operating said vibrator, said vibrator being movable out of engagement with said oscillatory member when said vibrator is folded, an arm pivoted concentrically with said oscillatory member for actuating said member, said arm being adjustable relative to said member to impart various amounts of movement to said vibrator, key levers for said typewriter, an operative connection between said key levers and said arm, a shiftable support for said oscillatory member and its actuating arm, and means for moving said support to bring said oscillatory member into re-engagement with said vibrator to retain said vibrator in folded position.

In testimony whereof I have signed my name to this specification on this 27th day of August, A. D. 1921.

OTTO A. HOKANSON.
